UNITED STATES PATENT OFFICE.

HERBERT B. TAYLOR, OF WESTFIELD, NEW JERSEY, ASSIGNOR TO HALL SWITCH & SIGNAL CO., A CORPORATION OF MAINE.

SWITCH AND SIGNAL INDICATION.

1,322,270.

Specification of Letters Patent.

Patented Nov. 18, 1919.

Application filed August 25, 1916. Serial No. 116,808.

To all whom it may concern:

Be it known that I, HERBERT B. TAYLOR, a citizen of the United States, and a resident of the town of Westfield, county of Union, 5 and State of New Jersey, have invented certain new and useful Switch and Signal Indications, of which the following is a specification.

My invention relates to certain new and 10 improved means of controlling traffic of trains of the type known as electric interlocking systems.

My present invention relates more specifically to a particular means of indication 15 of the correct functioning of such devices.

It has been the practice in operating 20 switches and semaphores electrically, to so arrange the devices and circuits that the tower man will have definite indication after he has pulled a controlling lever that the 25 function which the lever was intended to control has operated in the manner in which he so intended it. This has been accomplished in various manners, one being the employment of a direct current supply to 30 operate the function and then causing the function upon the completion of its operation to close a circuit through a separate and distinct source of alternating current supply, to 35 send an indication back to the tower man, and to operate a device therewith which would allow him to complete the full stroke of his lever.

One object of my invention is to obtain an 35 indication circuit with characteristics in distinct opposition to the circuit employed in the control of the devices. Another object of my invention is to simplify the wiring of such devices and avoid the necessity of 40 having power lines carrying different characteristic currents to the various functions to be operated.

Other objects and advantages will be understood by reading the specification and 45 will be more specifically described and claimed in the appended claims.

Referring to the figures, in Figure 1, I show diagrammatically the operating and control circuits for a switch machine and 50 also for the control of a semaphore.

In Fig. 2 I show a section of a current changing device taken longitudinally with the shaft.

In Fig. 3 I show a cross section taken 55 through A—A in Fig. 2.

In Fig. 4 I show a sectional side elevation of a controlling lever, showing the indication magnet and the method in which it controls the lever.

Referring to Fig. 1, I show a switch control lever 1 and signal control lever 2 which are located preferably in an interlocking tower, at any convenient place near the railroad track. Lever 1 carries tappet circuit controlling devices 3 and 4, arranged to 60 coat with the various contact springs 5, 6, 7, 8, 9, 10, 11 and 12, and lever 2 carries the tappet circuit controllers 13 and 14 arranged to coat with contact springs 15, 16, 17 and 18, a common return wire 19 is run from the 65 interlocking tower to every function to be controlled. A normal operating wire 20 and a reverse operating wire 21 are run to every switch operating machine and a control wire 22 is run to every semaphore operating mechanism. A source of direct current supply 23 is located preferably in the interlocking tower and connected by means of wire 24 to the common 19. The other side 70 of the source of supply 23 is connected by means of wire 25 to contact springs 6 and 3 and by means of wire 26 to the contact spring 16. The switch operating mechanism consists of a system of mechanical connections to the switch to be operated which 75 are driven through a suitable train of gearing by means of a direct current motor which is shown diagrammatically by means of the commutator 27 and opposing field windings 28, 29 and 30, 31. There are also 80 provided two systems of tappet circuit controllers 32 and 33 which operate in conjunction with the mechanism as hereinafter described.

In addition to this there are provided two 85 slow acting operating magnets 34 and 35 which control the contacts 36, 37, 38 and 39, 40, 41 respectively. The normal operating wire 20 is connected to contact springs 42 and 43 and by means of wire 44 to contact 45, and also to the contact 46 of the circuit controller 64 on the signal mechanism.

Reverse operating wire 21 is connected to contacts 46 and 47 and through wire 48 to contact 38. Contacts 10 and 12 are connected through indication magnet winding 49 to common 19, and contact 18 is connected through indication magnet winding 50 to common 19. The operating wire 22 is connected to one side of the hold clear magnet 110

51 of the signal mechanism and also to contact 52 of the circuit controller 62 and contact 53 of the circuit controller 63.

The mechanism of the semaphore 55 is operated through a suitable train of gears by means of a direct current motor diagrammatically shown by means of field winding 56 and commutator 57, and when the semaphore is in the clear position it is held by means of the hold clear magnet 51 in a manner well known in the art, the current passing from source of supply 23 through wire 26, contact spring 16, tappet circuit controller 13, contact spring 15, wire 22, hold clear coil 51, wire 58, and back through common 19, and wire 24 to source of supply.

As the circuits and mechanism are now diagrammatically shown the switch 54 is set for main line traffic and the semaphore 55 is in the clear position.

Referring to Fig. 4, it will be seen that the lever 2 is composed of a sliding member 79 carrying an operating handle 80 and arranged to slide horizontally on a bed 81. A slot 82 is formed in the under side of the member 79 and is provided with a locking dog 83, having sloping upper faces 84 arranged in such a manner that the dog 83 will be forced downward whenever it passes under a stop pin 85. The dog 83 also has a recess 86 formed in one of its sides and is provided with a coacting spring pressed ball 87 which will retain the dog in its upward or downward position until force is applied to move the same, either upward or downward. The slide member 79 is also provided with a cam groove 88 arranged to impart a vertical motion to a well known locking bar 89 by means of the connecting link 90 and the actuating roller 91. The locking bars 89 on the various levers are so interlocked that it is necessary to complete the full stroke of any one lever before another lever can be operated, this being accomplished in a manner which is old and well known in the art. The indication magnet consists of a laminated iron structure 92, carrying a coil 50 on one side of the same. A lever arm 93 is pivoted at a point 94 in such a manner that a shading coil 95 carried by the arm 93 and surrounding a portion of the iron core 92 will be free to travel outward along the section 96 of the core 92. Arm 93 also has an extension 97 which carries a shoe 98 operating in a vertical direction in a suitable guide 99, and pivoted to the arm 97 at a point 100. The operation of the lever is as follows:

Upon moving the handle 2 backward the sloping face 84 of the locking dog 83 will pass under stop pin 85 and the dog 83 will be forced downward until the projection 101 will pass down into the recess 102 of the bed 81. Should the operator then attempt to complete the stroke of his lever, the pro-

jection 101 of dog 83 will engage with the face 103 in the bed 81 and prevent its further movement. However, upon the reception of the alternating indication current which passes through indication magnet coil 70 50, the shading coil 95 will be forced outward on account of the induced current therein. This causes the shoe 98 to be raised thereby forcing the dog 83 upward until the projection 101 will be clear of the face 75 103. The dog is retained in this position by means of the ball 87. The lever will now be free, and the operator can complete the stroke of the same, thereby releasing his other levers in order that he may operate 80 these as desired.

The operations of the various devices to place the semaphore 55 at stop and move the switch 54 for take siding movements are as follows:

In order to move the semaphore 55 to the stop position the tower man operates lever 2, moving the same forward until the tappet circuit controller 14, bridges the contact springs 17 and 18 as shown in dotted lines 90 at 60 and tappet circuit controller 13 moves to the position shown at 61, opening the circuit between contact springs 15 and 16.

It will now be seen that the current supply to the hold clear coil 51 has been opened at 95 the contact springs 15 and 16, and semaphore 55 will commence to move to the stop position by gravity in the well known manner. This will rotate the armature and the commutator 57 of the signal motor backward. The circuit controllers 62, 63 and 64 are arranged to move through an angle of 90 degrees with the movement of the semaphore 55. It will thus be seen that when the semaphore 55 has almost reached the stop position, the circuit controllers 63 and 64 will wipe by and momentarily make contact with their respective contacts 53 and 45. Attached to the motor shaft are collector rings 65 and 66 and a commutator device 67. The collector rings 65 and 66 are connected to alternate contact segments of commutator 67 as shown at 68 and 69. It will be seen that as the semaphore 55 returns to the stop position closing circuit controller 64 and contact 45, a supply of direct current will pass from the source of supply 23 through wire 25, contact spring 6, tappet circuit controller 3, contact spring 5, wire 20, wire 44, contact 45, circuit controller 64 to collector 110 ring 66, through commutator 67, brush 70, primary winding 71 of transformer, brush 72, commutator 67, to collector ring 65, through wire 73, back through common 19, wire 24, to source of supply.

On account of the rotation of the commutator 67, the current passing through the primary winding of transformer 71, will be alternately reversed in direct relation to the speed of rotation of the commutator 67. At 130

the same time that circuit controller 64 and contact 45 close circuit controller 63 and contact 53 are closed, and in consequence of the alternation of current in the primary 5 winding 71, a secondary current will be induced in the secondary winding 74, which will be alternating in characteristic, and will pass through wire 75 to circuit controller 63, contact 53, wire 76, wire 22, wire 78, contact 17, tappet circuit controller 14, contact 18, indication magnet winding 50, back through common 19 to secondary winding 74. It will be seen that upon the energization 10 of indication magnet winding 50, that the lever 2 will be released and the tower man can then complete its stroke, causing the tappet circuit controllers to take up the position as indicated at 104 and 105, thereby leaving all the contacts on this lever open, 15 and unlocking all other levers which may now be safely operated. When the semaphore 55 has completed its movement to stop position the contacts 45 and 53 will have been again opened, thereby having left all 20 the indication circuits of the signal open.

In order to throw the switch 54 for the take siding movement, the tower man will move lever 1 forward until tappet circuit controllers 3 and 4 will take up the positions as indicated by dotted lines at 104' 30 and 105' respectively. This will close the circuit from source of supply 23, through wire 25, contact 8, tappet circuit controller 3, contact 7, reverse operating wire 21, contact 46, tappet circuit controller 106, contact 107, wire 108, through coil 35, wire 109 and back to common 19 and wire 24, to source of supply. This will energize the magnet 35 and close contacts 39, 40 and 41.

40 The current will then pass from wire 108 to contact 39, through wire 110, through field windings 31 and 30, through wire 111, through commutator 27 and armature windings, wire 112, back through common 19 and wire 24, to source of supply. This will operate the motor to operate the switch 54 to the siding position. Upon the commencement 45 of the operation of the switch, the circuit controller 32 is moved to a position which will cause the tappet circuit controllers 113, 114 and 115 to take the positions as shown in dotted lines at 116, 117, and 118. As the switch nears the completion of its movement, the circuit controller 33 is moved 50 over, causing the tappet circuit controllers 106, 119 and 120 to take up the positions shown in dotted lines at 121, 122 and 123. This will open the operating circuit to the motor through the tappet circuit controller 106 and the tappet circuit controller 119 will shunt the windings of the motor, through wire 112, commutator 27 and the armature of the motor, wire 111, reverse field coils 29 and 28, wire 124, wire 125, contact 60 126, tappet circuit controller 119, contact

127, wire 128, contact 40, which is still held closed on account of slow acting feature of magnet 35, wire 129, common 19, back to wire 112. This will act as a snubbing circuit to the motor and form a retardation device 70 at the completion of its operation. It will also be seen that as the tappet circuit controller 120 passes between contacts 47 and 131, the energy from source of supply 23 will pass through wire 25, contact 8, tappet circuit controller 3, contact 7, reverse operating wire 21, wire 132, contact 147, tappet circuit controller 120, contact 131, wire 133, wire 134, collector ring 135, commutator device 136, wire 137, primary 138 of 80 transformer, wire 139, back through commutator device 136, to collector ring 140, wire 141, common 19 and wire 24, back to source of supply.

On account of the rotation of commutator 85 device 136, the current in the primary 138 of the transformer will be alternating in characteristic and will, therefore, induce a secondary alternating current in secondary winding 142, which will pass through wire 90 143 through contact 41, wire 144, wire 44, normal operating wire 20, to contact 11, tappet circuit controller 4, contact 12, through indication magnet winding 49 and back through common 19, and wire 145, to secondary 95 142. This will operate the indication magnet of lever 1 in the same manner as described for lever 2 and release the same, in order that the tower man may complete its stroke. Upon the completion of the 100 stroke of the lever 1, the tappet circuit controllers 3 and 4 will take up the positions as indicated by dotted lines at 146 and 147 respectively. This will open the indication circuits at contacts 11 and 12, and will 105 leave the switch 54 in the take siding position.

The sequence of operations for the reverse movement of the switch are identical to the above, and it is therefore, not considered 110 necessary to describe the same.

After the switch has been returned to the normal position, leaving the circuits as shown in Fig. 1, the operation to clear the semaphore 55 is as follows:

Lever 2 will move forward to the full position, moving tappet circuit controllers 13 and 14 to the positions as shown and energy will pass from the source of supply 23 through wire 26, contact 16, tappet circuit 120 controller 13, contact 15, wire 22, contact 52, circuit controller 62, field winding 56, commutator 57 and armature of motor, wire 59, back to common 19 and wire 24 to source of supply. This will energize the motor and 125 cause the same to rotate and move the semaphore 55 to the clear position, when circuit controller 62 is opened, contact 52 cutting off energy from the motor, and leaving the semaphore 55 held in the clear position by 130

means of the circuit as previously described through the hold clear coil 51.

Although I have described one typical circuit and mode of operation of my device, it is apparent that many modifications may be made in the same without departing from the spirit of the invention, and I therefore do not wish to be specifically restricted to the particular form as shown 10 and described.

Having described my invention what I claim as new and desire to secure by Letters Patent is:—

1. In combination with a traffic controlling device, a direct current motor for operating the same, a source of direct current supply for said motor, means extraneous to the traffic controlling device for controlling said source, and means operatively connected to said traffic controlling device for changing the characteristics of a portion of said direct current supply to induce a secondary current to control the operation of said extraneous controlling means.

2. In combination with a traffic controlling device, a direct current motor for operating the same, a source of direct current supply for said motor, means extraneous to the controlling device for controlling said source, and means comprising a commutator for making a portion of said direct current supply alternating in characteristic to induce a secondary current to control the operation of said extraneous controlling means.

3. In combination with a traffic controlling device, a direct current motor for operating the same, a source of direct current supply for said motor, a current converting device extraneous to the motor and controlled thereby, a control lever, a three wire circuit between said traffic controlling device and said control lever, and means for impressing alternating current upon the 45 circuit to control the operation of the control lever.

4. In combination with a traffic controlling device, a source of direct current for operating the same, means operatively con-

nected to said traffic controlling device for 50 making a portion of said current alternating in characteristic, a control lever, connecting wires comprising a circuit between said traffic controlling device and said control lever, and means for impressing alternating 55 current upon the circuit to control the operation of the control lever.

5. In combination with a traffic controlling device, a source of direct current for 60 operating the same, means comprising a commutator operatively connected to said traffic controlling device for making a portion of said current alternating in 65 characteristic, a control lever, connecting wires comprising a circuit between said traffic controlling device and said control lever, and means for impressing alternating current upon the circuit to control the operation of the control lever.

6. In combination with a switch operating mechanism and a switch control lever, a semaphore operating mechanism and a semaphore control lever, a common source of direct current supply, and means associated with the semaphore mechanism to 70 change the characteristics of a portion of the direct current supplied to the switch control mechanism when the switch control lever is in a certain position to control the 75 operation of the semaphore control lever.

7. In combination with a traffic controlling device, a direct current motor for operating the same a source of direct current supply for said motor, a current converting device comprising a commutator operated 85 by said motor to convert a portion of said direct current to alternating current, a control lever, a circuit between said traffic controlling device and said control lever, a transformer for inductively impressing alternating current upon the circuit, and means included in said circuit comprising an inductively operated device to control the 90 operation of said control lever.

In testimony whereof, I have signed my 95 name to this specification.

HERBERT B. TAYLOR.
